UNITED STATES PATENT OFFICE.

HARRY FEDER, OF NEW YORK, N. Y.

DESIGN FOR SKIRT-BINDING.

SPECIFICATION forming part of Design No. 29,556, dated October 25, 1898.

Application filed September 26, 1898. Serial No. 691,941. Term of patent 14 years.

To all whom it may concern:

Be it known that I, HARRY FEDER, a citizen of the United States, and a resident of New York, in the county and State of New York, have invented and produced a new and original Design for Skirt-Binding, of which the following is a specification, reference being had to the accompanying drawings, forming a part thereof.

10 The leading features of my design consist in a skirt-binding presenting in side elevation when looked at from one side a plain head portion and a brush-like edge along the edge of the plain head portion, and when viewed in side elevation from the opposite side presenting a plain head portion, a brush-like edge, and a mottled band intermediate of the plain head portion and brush-like edge. When viewed in section, the binding presents a thin head portion, a brush-like edge, and a mottled band offset from one side of the thin head portion.

15

20

In the accompanying drawings, Figure 1 is a view of the binding in side elevation. Fig. 2 is a similar view from the opposite side, and Fig. 3 is a view in transverse section.

A represents the plain head portion; B, the brush-like edge, and C the mottled band intermediate of the plain head portion and brush-like edge on one side of the binding.

What I claim is—

The design for a skirt-binding, substantially as herein shown and described.

In testimony that I claim the foregoing as my invention I have signed my name, in presence of two witnesses, this 24th day of September, 1898.

HARRY FEDER.
